G. F. ZAUN.
SECTIONAL FLOOR RACK.
APPLICATION FILED JUNE 16, 1920.

1,405,655.

Patented Feb. 7, 1922.

UNITED STATES PATENT OFFICE.

GEORGE F. ZAUN, OF SAN BERNARDINO, CALIFORNIA.

SECTIONAL FLOOR RACK.

1,405,655.

Specification of Letters Patent. Patented Feb. 7, 1922.

Application filed June 16, 1920. Serial No. 389,531.

To all whom it may concern:

Be it known that I, GEORGE F. ZAUN, a citizen of the United States, residing at San Bernardino, in the county of San Bernardino and State of California, have invented new and useful Improvements in Sectional Floor Racks, of which the following is a specification.

This invention relates to sectional floor racks and has for an object the provision of a floor rack or floor racks which will present a smooth surface on either side of said rack or racks. Another object is the provision of a floor rack or floor racks which may be placed within a refrigerator box car and which floor racks may be either placed on the floor of the car or in an inoperative position against a side wall of the car, and which racks when so placed against a side wall of the car will present a smooth surface so that objects may be stored against the same without any fear of damage to said objects.

Another object is the provision of a series of floor racks, each rack of which goes to form a unit and which units combine with other units when desired.

In practicing the invention I provide a series of racks having superposed longitudinal and transverse members and which racks are hinged or pivotally held to a portion of the interior of the car, so that each individual section may be revolved into an operative position on the floor or an inoperative position against the side wall thereof. The racks are so constituted that one rack at a time may be lowered to the floor of the car and articles such as boxes placed thereon, a rack at a time.

It has been found that in shipping fruit in refrigerator box cars a circulation of air throughout the car is necessary. To accomplish a circulation, it is customary to provide some form of removable rack upon which boxes containing fruit or perishable goods are placed. Usually the exchange handling the perishable goods provides racks and when the load reaches its destination the racks are usually thrown out of the car and destroyed. Thus a great waste of money and time is occasioned. With these racks, however, it is intended that each unit section going to compose these floor racks should become an integral part of the car.

Furthermore, it is not intended that any change in the general construction of the

car should be made. Each section going to compose the floor racks is hinged at one end thereof to the car floor or the car wall. In fact, the hinge is of a continuous nature; that is to say, there is a series of sockets arranged upon the floor of the car near a wall thereof and a series of sockets on each of the floor rack sections. A long pin is run through each of said sockets. Each floor rack extends substantially in length the entire width of the car and each section in addition is made of a width sufficient so that trucking may be performed on the smooth floor up to the floor rack and the boxes trucked thereto readily placed thereon without the necessity of trucking over the floor racks. When one floor rack section has been filled, another floor rack section is lowered and it in turn covered with boxes. When both sides of the car have been filled, a press may be run in between the two racks and the loads contained on said racks moved in order to compactly store the same. As the racks are universally hinged, the racks will move as the load moves, thus aiding in the compact arrangement of the same.

I likewise provide racks intended to fit within the doorways of the car. The head- ers now used in refrigerator box cars are standard in height and it is a requirement that no object be placed upon the floor which will so raise the height of the floor that there will not be sufficient clearance for the head of an operator who is trucking material within the interior of the car. If it were intended to use racks that were on the floor at all times, it would be necessary to cut the door-head slightly, but inasmuch as the principal bracing elements of the car are contained above and below the door-head, this would perceptibly weaken the car construction. Accordingly, I provide floor racks which are provided with swinging levers which allow the floor racks to be raised from the floor of the car at the entrance doors thereof and swung to the roof of the car and held suspended when so swung by lock means.

After the car has been unloaded, each of the racks may be swung into an inoperative position against a side wall of the car and releasable means are provided for holding each of the racks in an inoperative position. And when the racks are so held in an inoperative position, a smooth surface is pre-

sented so that the car may be readily re-loaded without any damage to any material placed therein, as has been mentioned.

The invention has for further objects the provision of improved sectional floor racks which will be superior in point of relative simplicity and inexpensiveness, taken in conjunction with utility, durability and general serviceability.

10 With the above and other objects in view, the invention consists in the novel and useful provision, formation, construction, combination, association and inter-relation of parts, members and features, all as disclosed 15 in the accompanying drawing, described in the following specification, and finally pointed out in claims.

In the drawing:

Figure 1 is a fragmentary isometric view 20 of a refrigerator box car with improved sectional floor racks arranged therein;

Figure 2 is a cross sectional end elevation illustrating the manner in which a hinged sectional floor rack may be revolved to the 25 floor of the car or against a side wall thereof;

Figure 3 is a fragmentary side elevation and taken on the line x^3-x^3 , Figure 2, and looking in the direction of the appended 30 arrows;

Figure 4 is a cross sectional end elevation showing certain features of construction, and taken on the line x^4-x^4 , Figure 3, and looking in the direction of the appended 35 arrows;

Figure 5 is a sectional end elevation showing the general arrangement and construction of floor racks used at the entrance openings of the refrigerator box car;

40 Figure 6 is an isometric perspective view, parts being shown fragmentarily, of certain details of construction of the rack member adjacent the bulk-head wall of a refrigerator box car.

45 Corresponding parts in all the figures are designated by the same reference characters.

Referring with particularity to the drawing, A designates a refrigerator box car in which there is a bulkhead wall a located at 50 one end of the car A. B designates the floor racks.

The floor racks B comprise in the main transverse members 1 and longitudinal members 2 and 3. Referring to the drawing, it 55 will be observed that the longitudinal members 2 and 3 are superposed and that the members 1 act as binders therefor. Each of the racks B comprises a plurality of longitudinal and transverse members, and the 60 longitudinal members are superposed one above the other. Each of the racks B may be made up of a plurality of the superposed longitudinal members 2 and 3 and each of the longitudinal members are spaced from 65 one another so as to provide an air space.

A plurality of sectional racks B is provided upon each side of the car. Each of the rack members B is of a longitudinal length sufficient so that upon revolving the same from a position as 5 to a position shown as 6 in 70 Figure 2, the rack B will extend practically the width of the car. Each of the rack sections B is provided with socketed portions 7 and the floor 8, as at 9, is provided with a series of sockets 10. A long pin alternately 75 runs through the sockets 10 on the floor 8 and the sockets 7 connected to the sections B. This arrangement, of course, provides means by which each of the sections on one side of the car may be hingedly mounted. 80 When the rack sections B are revolved into a position such as shown at 5 in Figure 2, a means such as 10^a serves to retain the rack sections B in an upright position.

The bulkhead wall a , shown at one end 85 of the refrigerator box car, as 11, may be revolved from its position as shown in Figure 3, as 12, upwardly as shown by the dotted line to the position 13. This is standard practice and it is customary to revolve 90 the bulkhead wall a into such a position as 13 when the car has finally reached its destination and it is not to be used as a refrigerator car upon its return trip. The bulkhead wall a when revolved to the position 95 13 may be locked and the space originally confined by the bulkhead wall, which space as 14 was intended to contain ice, may now be utilized for storing goods, wares or merchandise. However, as the bulkhead wall a 100 is of a width corresponding to the width of the car, it would ordinarily be impossible to swing the bulkhead wall a into the position 13 shown in Figure 3 if all the rack members B were pivotally joined or hinged to the car. Therefore, one of the rack members B, as b , is longitudinally hinged as at 105 15 so that said rack b may revolve upon itself as shown in Figure 3. When the revolving process has been accomplished, a 110 space is left so that the bulkhead wall a may be revolved into an inoperative position adjacent the roof of the car, after which the rack b may then be returned to its normal position and then revolved against the 115 side wall of the car as at 16, Figure 4.

It will be observed that each of the hinged rack members B has the top longitudinal members 2 with their ends projecting beyond the lower longitudinal members as 3, 120 and in order that the rack member b may likewise present a top surface equal in longitudinal length to longitudinal members 2 an end portion as 17 of the same is hinged, as at 18. It is necessary that the 125 end portion as 17 be hinged so as to drop down in order that when the bulkhead wall a is revolved into an inoperative position, as shown at 13, the bulkhead wall may rest upon the ends 19 and 20 presented by the 130

hinged end portion of the member *b* and the member 17 respectively. If the member *b*, constituting one of the rack members *B*, should be made of a longitudinal length 5 corresponding to the longitudinal length of the other rack members, the height would be too great so that it could not be revolved against a side wall of the car, and yet at the same time have the bulkhead wall *a* in an 10 inoperative position. As has been above stated, it is not desired to change the car construction in the least.

The sectional racks *B* as *c*, arranged respectively adjacent the door openings *d* of 15 the car *A*, are so constituted that they may be swung into a position adjacent the top of the car or onto the floor thereof. To accomplish this, I provide each of the racks *c* with a pair of pivoted lever arms *e*.

20 Referring to Figure 5 which illustrates the method by which the racks *c* are joined to the respective lever arms *e*, it will be observed that when one of the racks as at 21 has been revolved from the position shown 25 by the Roman numerals I, II and III and to the final position IV, it will be seen that the racks *c* have simply turned upon the arms *e* as at 22. In position I shown by dotted lines the rack has been maintained 30 against the roof of the car. At position II the lever arms *e* have moved upon an arc and the rack now hangs directly downward. At position III the rack has been tipped sufficiently so that an end portion as 23 will 35 be ready to contact with the floor 8, and at position IV the rack is now resting upon the floor. When the rack is in an elevated position, as shown in position I, Figure 5, by dotted lines, it may be locked to the roof of 40 the car by means 24 which may comprise angle hooks. The lever arms *e* are joined to eye brackets 25 as at 26 and 27 and 28 and 29. Thus it will be seen that all trucking 45 may be within the car and may be upon the smooth floor surface 8 of the car, only such racks *B* being lowered as the load in the car gradually increases and additional racks are necessary. Thus there will be no trucking over the racks. When the car has been 50 filled up to the door portions, one of the racks *c* may be lowered by the method just described and said rack filled, after which the other may be lowered and that rack filled. The particular arrangement shown 55 therefor complies with all lawful requirements in that the racks *c* may be placed into or out of position and held when in an inoperative position.

I likewise provide spring hooks 30 in the 60 form of the figure 4 and which spring hooks cooperate with each of the pivoted lever arms *e* and serve to retain said lever arms in an upward position, as shown in Figure 5. By making the spring hooks in 65 the form of a figure 4 the nose portion will

allow the lever arms *e* to be pushed up and hooked similarly to the action of a door catch. The members 30 likewise act to prevent the racks *c* from in any manner becoming loose when arranged adjacent the 70 roof of the car and descending on the head or heads of any person or persons entering the car.

It is obvious that many changes, variations and modifications may be made in 75 departure from the particular description and the showing of the accompanying drawing, and adapting the invention to varying conditions and requirements in use and service, without departing from the true spirit 80 of the invention.

What I claim and desire to secure by Letters Patent is:

1. A floor rack having angularly related superposed members spaced to provide air 85 openings; said superposed members being arranged in longitudinal and transverse series; with the said longitudinal members mounted on opposite sides of said transverse members. 90

2. In a floor rack, the combination, with the floor rack having transverse members, and longitudinal members mounted on opposite sides of said transverse members, with said members spacedly arranged to provide 95 air openings, a refrigerator box car and means by which said floor rack may be pivotally mounted within said car whereby the floor rack may either be revolved into a position on the floor of the car or against a side 100 wall thereof.

3. In a floor rack, the combination, with the floor rack having transverse members with longitudinal members mounted on opposite faces of said transverse members 105 spacedly arranged to provide air openings, a refrigerator box car and means by which said floor rack may be pivotally mounted within said car whereby the floor rack may either be revolved into a position on the floor 110 of the car or against a side wall thereof; means being provided for holding the floor rack when arranged against a side wall of the car.

4. In a floor rack, the combination, with 115 the floor rack having angularly related superposed members arranged in longitudinal and transverse series and spaced to provide air openings, with the said longitudinal members mounted on opposite sides of the 120 said transverse members, a refrigerator box car, and means by which said floor rack may be pivotally mounted within said car, whereby the floor rack may either be revolved into a position on the floor of the car or against 125 a side wall thereof, and means for retaining said rack when in the latter position.

5. In combination, sectional floor racks, having transverse members with longitudinal members mounted on opposite faces of 130

said transverse members spacedly arranged from each other to provide air openings, a refrigerator box car, and means by which said racks are hingedly mounted within and to the car, whereby the racks may be removably held on the floor of the car or maintained in an upright position against a side wall of the car.

6. In combination, sectional floor racks, 10 having transverse members with longitudinal members mounted on opposite faces of said transverse members spacedly arranged from each other to provide air openings, a refrigerator box car, and means by which 15 said racks are hingedly mounted within and to the car, whereby the racks may be removably held on the floor of the car or maintained in an upright position against a side wall of the car; means being provided 20 for retaining the racks when in an upright position.

7. In a refrigerator box car, the combination, with the refrigerator car provided with an ice bulkhead wall adapted to be swung 25 from an operative position to an inoperative position adjacent the roof of the car, floor racks, each one of which forms a unit section; said floor racks comprising transverse members provided with longitudinal members 30 mounted on opposite faces thereof with said members spacedly arranged from each other; means by which said sections are hingedly mounted to and within said car; a unit section adjacent the bulkhead wall being hinged longitudinally to allow a portion of same to be revolved upon itself and thus permit the bulkhead wall to be freely swung from an operative to an inoperative position.

8. In a refrigerator box car, the combination, with the refrigerator car provided with an ice bulkhead wall adapted to be swung 40 from an operative position to an inoperative position adjacent the roof of the car, floor racks, each one of which forms a unit section, and means by which said sections are hingedly mounted to and within said car; a unit section adjacent the bulkhead wall be-

ing hinged longitudinally to allow a portion of same to be revolved upon itself and thus permit the bulkhead wall to be freely swung 50 from an operative to an inoperative position; said last named section likewise being provided with hinged extensions, whereby when the bulkhead wall is in an inoperative position said section may be freely placed 55 against a side wall of the car and will serve to retain the bulkhead wall in its inoperative position.

9. In a floor rack, the combination, with the floor rack having transverse members provided with longitudinal members mounted on opposite faces of said transverse members with said members spacedly arranged to provide air openings, a refrigerator box car, and means for removably holding said 65 rack either on the floor of said car or suspended adjacent the roof thereof.

10. In a floor rack, the combination, with the floor rack having transverse members provided with longitudinal members mounted 70 on opposite faces of said transverse members with said members spacedly arranged to provide air openings, a refrigerator box car, and means for removably holding said rack either on the floor of said car or suspended adjacent the roof thereof; and means 75 likewise being provided for locking the rack when so suspended.

11. In combination, sectional floor racks having transverse members provided with 80 longitudinal members mounted on opposite faces of said transverse members with said members spacedly arranged to provide air openings, a refrigerator box car, and means for removably holding said racks either on 85 the floor of said car or suspended adjacent the roof thereof.

In testimony whereof, I have signed my name to this specification in the presence of two subscribing witnesses.

GEORGE F. ZAUN.
